Application January 25, 1943, Serial No. 473,446
In Canada December 21, 1942

2 Claims. (Cl. 2—221)

Introduction

This invention relates to garments and more particularly to maternity garments.

Objects

A principal object of the invention is to provide a garment like a skirt or slacks in which provision is made for easy adjustment to figures of different sizes. It is a further object of the invention to provide a garment of this kind suitable for use by expectant mothers. A further object is to provide a garment of this nature in which the symmetry is not destroyed by the adjustment to different sizes. A still further object is to provide such a garment which is simple to manufacture and convenient to wear.

These objects and others are accomplished according to a preferred embodiment of the invention by a garment structure including a back and front permanently secured together at each side through a major portion of their outer edges but free adjacent the top of the garment to form plackets. The corners of the front are adapted for fastening to the back at the top of the plackets. The back includes extensions or flaps and a waistband providing a foundation structure to encircle the body. The front is also provided with excess material for formation of a plurality of pleats. Means are appropriately positioned for gathering in the front to form the pleats neatly and inconspicuously.

Drawing

The invention will be further understood by reference to the accompanying drawing illustrating a preferred embodiment, and in which,

Figure 1 is a front view of the garment, in this case a skirt, gathered in to its minimum width, the foundation structure formed by the back piece and extensions thereof being indicated in dotted lines.

Figure 2 is a front view of the skirt shown in Figure 1, in this case, expanded to its maximum width.

Figure 3 is a rear view of the skirt showing the flaps of the back spread out.

Figure 4 is a top view of the skirt held in an open position to show the adjustable parts in substantially the relative position they will assume when it is worn, with the front drawn in to form pleats as in Figure 1.

Figure 5 is an enlarged fragmentary view of the top portion of one side of the front of the garment showing the structure for gathering in the front of the garment to form pleats.

Detailed description

Referring more particularly to the drawing, the preferred form of the garment shown is made up of back pieces 11 and front pieces 12 respectively secured together and to each other to make up the garment. The back pieces are each provided with a surplus portion or extension 15. The back is provided with a belt 16 extending about the top of the back piece and its surplus portions so as to make up a body-encircling foundation structure. The belt 16 is provided with a front central portion 18 including a buckle 19 to allow for adjustment to various girths. The purpose of such a structure, when positioned substantially as indicated in Figures 1 and 4, is to provide mutual support for the garment and for the wearer's body. The back is joined to the front as will be described.

20 The front of the garment is made considerably over-size, leaving provision for the formation, as required, of large adjustable pleats 20. Lacing 21 extending through eyelets 23 makes it possible to let the front piece out to its full width or to draw the material in to form pleats as required.

25 The front and back pieces are joined together at their outside edges by lines of stitching 30 which extend from the hem of the skirt up to a point somewhat below the top thereof, that is, just below the bottom edge of the surplus 15 leaving a side opening or placket 35 at each side of the skirt. Buttons and buttonholes 41 or other suitable fastening means are provided to fasten the top edges of the front and back pieces together. The buttons may be moved as desired to afford further expansion of the perimeter of the top of the garment. The top parts of the front piece from the termination of the line of stitching 30 to the top conceals the under-structure formed by the surplus piece 15 and the belt 16.

30 In the case of slacks, the structure is similar with the exception that the front and back pieces are divided centrally and joined together to form legs, as will be clearly understood.

Operation and advantages

35 It is seen that this garment is adjustable for waists of various sizes, making it particularly suitable for maternity use. There are several ways in which the garment is adjustable, namely, through the adjustable pleats in the front piece; by moving the buttons or fasteners 41; and by adjusting the buckle 19. The adjustable features are concealed and do not accentuate the figure in any way, the garment giving the appear-

ance of normal dress. The garment, whether in expanded or contracted condition, maintains its symmetry. At the same time, while there are plackets at each side of the skirt, there are no open portions to allow exposure of the wearer's lingerie.

The structure formed by the back piece, its surplus portions and the belt constitute a supporting structure to hold the garment up and give a sense of security to the wearer. The structure of the front piece permits its adjustment for various sized waists while still retaining a normal appearance.

The lower garment described above and illustrated in the drawing is a preferred form of the invention which has been found unusually practical. It might be desirable to join the lower garment with an upper garment, making a dress. The design might be applied to an undergarment. It might also be desirable to utilize certain of the adjustable features without others or in conjunction with other adjustable features. In any event, it will be understood that, without departing from the spirit of the invention or the scope of the claims, these and various other modifications may be made in the specific expedients described. The latter are illustrative only and not offered in a restricting sense, it being desired that only such limitations shall be placed thereon as may be required by the state of the prior art.

The sub-titles used throughout the specification are merely to simplify reference thereto and should otherwise be disregarded.

I claim:

1. A lower outer waist-supported garment adapted for maternity use, comprising, a back part and a front part, a supporting structure extending from the back part adjacent the waist-line thereof and adapted to encircle the front of the body to give mutual support to the garment and to the body of the wearer, said supporting structure being adjustable to allow expansion at the waist-line, a front part connected to the back part adjacent the side edges thereof for a portion of the height of the front and back parts, top portions of the edges of the back and front parts remaining unjoined to leave an upper portion of the front part, fastening means for connecting said free upper portion to the back part adjacent the waist-line whereby said upper portion is supported in wearing relation to said supporting structure and completely shielding it, said upper portion having an excess of material and means for gathering in or letting out said excess material thereby to regulate the width of said upper portion.

2. A lower outer waist-supported garment adapted for maternity use, as claimed in claim 1 wherein the means for gathering in and letting out said excess material include spaced apart eyelets adjacent the waist-line and a drawstring in said eyelets.

LILLIAN HERSCOVICI.
